United States Patent

Des. 236,107
Patented July 29, 1975

236,107

AUTOMOBILE WHEEL

Delmer D. Scott, Encino, Calif., assignor to
Permacast Corp., Compton, Calif.

Filed June 21, 1974, Ser. No. 483,937

Term of patent 14 years

Int. Cl. D12—16

U.S. Cl. D12—211

Fig. 1.

Fig. 2.

FIG. 3.

FIG. 4.

FIG. 1 is a front elevational view of an automobile wheel embodying my new design;

FIG. 2 is a side elevational view thereof;

FIG. 3 is a rear elevational view thereof; and

FIG. 4 is a cross-sectional view thereof taken on the line 4—4 in FIG. 1.

I claim:

The ornamental design for an automobile wheel, as shown.
